[57] CLAIM

The ornamental design for a bird feeder seed baffle, as
shown and described.

DESCRIPTION

FIG. 1 is a perspective view of a bird feeder seed baffle
showing our new design;

FIG. 2 is a top plan view thereof;

FIG. 3 is a bottom plan view thereof;

FIG. 4 is a front elevational view thereof;

FIG. 5 is a side elevational view thereof; and,

FIG. 6 is a perspective view showing the seed baffle
installed within a bird feeder.The broken-line portions in FIG. 6 are for illustrational
purposes only and form no part of the instant design.FIG. 1

FIG. 2

FIG. 3

FIG. 4

FIG. 5

FIG. 6
